UNITED STATES PATENT OFFICE

160,921

HOLDER FOR TISSUES OR THE LIKE

Herbert S. Chase and George C. Mathes,
New York, N. Y.

Application March 3, 1950, Serial No. 8,312

Term of patent 7 years

(Cl. D87—3)

To all whom it may concern:

Be it known that we, Herbert S. Chase and George C. Mathes, both citizens of the United States of America and residents of New York city, county of New York, and State of New York, have invented a new, original, and ornamental Design for a Holder for Tissues or the like, of which the following is a specification, reference being had to the accompanying drawing, forming part thereof, wherein:

Figure 1 is a front elevational view of a holder for tissues or the like showing our new design.

Figure 2 is a side elevational view thereof; and
Figure 3 is a rear elevational view.

We claim:

The ornamental design for a holder for tissues or the like, substantially as shown.

HERBERT S. CHASE.
GEORGE C. MATHESES.
